ELECTRODE ASSEMBLY FOR ELECTRON- DISCHARGE TUBES

Paul W. Stutsman, Needham, Mass., assignor to
Raytheon Manufacturing Company, Newton,
Mass., a corporation of Delaware

Application June 1, 1945, Serial No. 597,056

7 Claims. (Cl. 250—27.5)

1

The present invention relates to electron discharge tubes.

One of the objects of the present invention is to provide an electron discharge tube with means for protecting elements of the electrode assembly from arcing and electron bombardment.

Another object of the present invention is to protect elements of the electrode assembly from deposits resulting from the flashing of the getter.

These and such other aims and objects of the present invention as may hereinafter appear will be best understood from the following description taken in connection with the accompanying drawing of one embodiment of the invention, herein presented for illustrative purposes.

In the drawing:

Fig. 1 is a longitudinal section on line 1—1 of Fig. 2.

Fig. 2 is a transverse section taken on line 2—2 of Fig. 1.

The tube shown in the drawing illustratively consists of a high voltage rectifier tube comprising an hermetically sealed envelope 2 containing an electrode assembly comprising a filament cathode 4, a grid 6 surrounding said cathode, and a cylindrical anode 8 (see Fig. 2) surrounding said grid. Said filamentary cathode is welded at its upper end to one end of a spring 10 which is welded at its other end to a conducting rod 12 (see Fig. 2). Said conductor rod 12 is welded at its lower end to a conductor 16. Said filamentary cathode extends through corresponding openings in upper and lower spacing members 32 and 34, hereinafter more fully described, and is welded at its lower end to a conductor 14.

The grid 6 is wound around and supported by two diametrically opposed conducting rods 18 and 20, one of which, the rod 20 for example, is welded at its lower end to said conductor 14. The cylindrical anode 8 is supported by two diametrically opposed conducting rods 22 and 24 extending longitudinally of and welded to said anode plate 8 on the outer side of the latter. The lower ends of said two rods 22 and 24 are connected to each other by a metal ribbon 26 welded to a conductor 28 (see Fig. 2). Said conductors 14, 16, and 28 are butt-welded to lead-in conductors sealed through the base 30 of the tube and projecting therefrom as exterior contact prongs. The upper and lower spacing members above referred to consist of insulating plates 32 and 34, preferably of mica, provided at their edges with resilient teeth 36 (see Fig. 2) that yieldingly engage the lateral wall of said envelope and brace said spacing members laterally. Said plates 32

and 34 are provided with suitably spaced perforations through which are threaded the said conducting rod 12 for the cathode, said grid supporting rods 18 and 20 (see Fig. 2), and the anode supporting rods 22 and 24.

In accordance with the present invention, the portions of said plate supporting rods 22 and 24 that project above and below said anode plate 8 and are thus exposed to electron bombardment are protected from such bombardment by suitable means. Said means herein illustrated comprises insulating caps 38 enclosing the exposed upper end portions of said rods and insulating sleeves 40 enclosing the exposed lower end portions of said rods. Said caps and sleeves may be made of any suitable insulating material, preferably of glass. The lower edges of said caps 38 may rest upon the upper edge of said anode plate 8, and the lower edges of said sleeves 40 may rest upon suitable pins 41 projecting from said rods 22, 24 and welded or otherwise fastened thereon. The caps 38 and sleeves 40 also reduce the probability of arcing between said rods and said cathode or other parts of the assembly or at the junctions of conducting and non-conducting parts, such as said insulating plates 32 and 34, and along leakage paths. Said caps also protect said rods 32 and 24 from the deposit thereon of condensation products freed by the flashing of the getter. The latter is shown at 42 and is carried by a conductor 44 welded to an ear 46 projecting from the upper edge of a conducting shield 48 through said upper spacing plate 32. Said shield comprises a metal cylinder surrounding the electrode assembly and provided upon the lower edge with ears 50 projecting through perforations in the lower spacing plate 34 and welded respectively to two bent conductors, only one of which is shown at 52. Said two bent conductors 52 are butt-welded to lead-in conductors 54 and 56, respectively, (see Figs. 1 and 2) sealed through said tube base 30 and projecting therefrom as exterior contact prongs. The conductors 52 support said shield at diametrically opposed points, and they also support said spacing plates 32 and 34 and the electrode assembly. Said shield completely surrounds the electrode assembly and protects the latter from objectionable effects of electrical charges accumulated upon the inner wall of the envelope 2 by electron bombardment.

I am aware that the present invention can be embodied in other specific forms without departing from the spirit or essential attributes thereof, and I therefore desire the present description

to be considered in all respects as illustrative and not restrictive, reference being had to the appended claims, rather than to the aforesaid description, to indicate the scope of the invention.

What is claimed is:

1. An electrode assembly comprising an insulating electrode spacing member, an insulating sleeve inserted through a perforation in said spacing member, an electrode supporting rod having a portion thereof surrounded by said insulating sleeve, and means carried by said electrode supporting rod for supporting said insulating sleeve.
2. An electrode assembly comprising an insulating electrode spacing member, an insulating sleeve inserted through a perforation in said spacing member, and an electrode supporting rod having an end portion inserted in said sleeve, said sleeve being closed over the end of said electrode supporting rod inserted therein.
3. An electron-discharge tube comprising a filamentary cathode, an anode surrounding said cathode, insulating electrode spacing members, insulating sleeves inserted through said spacing members, anode supporting rods having portions thereof surrounded by said sleeves, and means carried by said anode supporting rods for supporting said sleeves.
4. An electron-discharge tube comprising a filamentary cathode, an anode surrounding said cathode, insulating electrode spacing members, anode supporting rods having their end portions threaded through said spacing members, glass sleeves surrounding said end portions of said rods, and means carried by said rods for supporting said glass sleeves.
5. An electron-discharge tube comprising a filamentary cathode, an anode surrounding said cathode throughout a portion of the length of said cathode, insulating electrode spacing mem-

bers, anode supporting rods having portions projecting beyond the ends of said anode and threaded through said spacing members, and insulating means surrounding said portions of said rods that project beyond the ends of said anode.

6. An electron-discharge tube comprising a cathode, an anode surrounding a portion of said cathode, insulating electrode spacing members, anode supporting rods having portions projecting beyond the ends of said anode and threaded through said spacing members, and insulating means surrounding said portions of said rods that project beyond the ends of said anode.

7. An electron-discharge tube comprising a filamentary cathode, an anode surrounding said cathode throughout a portion of the length of said cathode, insulating electrode spacing members, anode supporting rods having portions projecting beyond the ends of said anode and threaded through said spacing members, and insulating means surrounding said portions of said rods that project beyond the ends of said anode, said insulating means completely enclosing said portions of said rods that are threaded through one of said spacing members.
